CLAIM

The ornamental design for a confectionary snack packaging, as shown and described.

DESCRIPTION

FIG. 1 is a front view of a confectionary snack packaging, showing my new design; and,

FIG. 2 is a rear view of the confectionary snack packaging. The details shown in broken lines are for the purpose of illustrating parts of the article and form no part of the claimed design.

1 Claim, 2 Drawing Sheets Fig. 1

Fig. 2
